FURNACE

Elmer H. Berryman, San Francisco, Calif.

Application October 18, 1933, Serial No. 694,103

7 Claims. (Cl. 22—57.1)

This invention relates in general to casting furnaces and in particular to a pneumatically operated dental casting furnace.

To make a casting that is exactly complementary to the mold from which it is made the casting material should of course be maintained in a molten state until it has completely filled the mold. This requires that the temperature of the casting material be maintained above its melting point during the entire process and that a substantially constant and uniform pressure be applied to it during the casting operation. Since most materials contract upon cooling and solidifying it is essential in making a dental casting that the casting material cools and solidifies progressively from the point furthest away from the sprue hole to the entrance of the sprue hole. I have found that a closed air tight muffle forms the most convenient equipment in which a technique of this kind can be carried out.

In this method of making castings the investment ring is subjected to a more continuous application of elevated temperatures and consequently some means must be resorted to to protect the ring as much as possible.

The length of time required to melt the casting material preparatory to casting depends not only upon the temperature used but also upon the amount of material and its melting point. The simplest method of determining when the casting material has reached a molten state is to look at it periodically. The light given off from a molten metal is very intense and I have therefore found it desirable to view the material through a colored sight glass or window.

In general the object of my invention is the provision of a pneumatically operated casting furnace by which the casting material can be maintained above the melting point during the entire operation and subjected to a substantially constant and uniform pressure during the actual casting period.

Another object of my invention is the provision of a pneumatically operated casting furnace the muffle of which has a substantially negligible volumetric gas capacity in comparison to the gas receiver which serves as the source of pressure.

A further object of my invention is the provision of a furnace having a colored window so that the action of the molten metal within the muffle may be watched.

Another object of my invention is the provision of an investment ring having a set of bayonet pins at each end so that the ends are interchange-

able, one set of pins being used to lock the investment ring in place while the other set serves as a means by which the ring may be gripped by a pair of tongs having apertured ends adapted to engage the pins.

Still another object of my invention is the provision of a sprue holder and crucible former to be used in conjunction with an investment ring to form a protective layer of investment material over that end of the ring which is subjected to the most intense heat.

Another object of my invention is the provision intermediate the furnace and the source of air pressure of a receiver having a volumetric capacity such that the volumetric capacity of the muffle is negligible in comparison to it.

The invention possesses other advantageous features, some of which with the foregoing, will be set forth at length in the following description where I shall outline in full the form of my invention which I have selected for illustration in the drawings accompanying and forming a part of the present specification. In said drawings, I have shown one form of my invention, but it is to be understood that I do not limit myself to such form, since the invention as set forth in the claims, may be embodied in a plurality of forms.

Referring to the drawings:

Figure 1 is a vertical mid-section of the casting furnace taken on the broken line 1—1 of Figure 2.

Figure 2 is a horizontal section taken on the line 2—2 of Figure 1.

Figure 3 is a vertical mid-section taken through the investment ring and its associated sprue holder and crucible former.

Figure 4 is a diagrammatic representation of the furnace in combination with a source of high pressure and an intermediate gas receiver.

Figure 5 is a vertical midsection of a larger investment ring of modified construction.

Figure 6 is a section on the line 6—6 of Figure 4.

As best shown in Figure 1 the furnace comprises a generally cylindrical metal casing 1 provided at its base with inwardly and outwardly extending flanges 2 and 3 respectively and bolted to the outwardly extending flange of a depending generally semi-circular carriage or apron 4. If desired a gasket 4' may be placed between the casing 1 and the apron 4 to decrease the transfer of heat between these two elements. Supported on the upper face of the flange 2 is a hollow inverted funnel shaped muffle 5 having an upwardly extending stem 6. Forming part 55

of the muffle 5 is an annular plate 7 the periphery of which forms a channel 8 which accommodates a gasket 9. The peripheral edge of the muffle 5 rests on the gasket 9 and its lower surface overlies an annular refractory plate 10. The muffle 5 and its associated plate 7 are made of quartz or other refractory material. Fused to the upper end of the stem 6 is a colored quartz window 11.

10 Diametrically opposed pockets 12 and 13 formed on the outer surface of the casing 1 accommodate electric contact members 14 and 15 which are bolted in place as clearly shown in Figure 1. The contact members and the bolts 15 by which they are to be secured to the casing may be keyed to prevent any relative rotation and are insulated from the casing by means of insulating washers 16 and mica tubes 16'. The free ends of the contact members 14 and 15 are 20 forked or bifurcated and are formed with curved surfaces 17. As shown in Figure 2 two sets of spaced contact members are provided. Spaced electric heating elements 18 and 19 are 25 symmetrically disposed within the muffle 5, one on either side of the muffle stem 6. To the ends of these heating elements are sweated Asc alloy caps 20 provided with outwardly extending vertical webs 20' and with curved shoulders 21 complementary to the curved surfaces 17 of the 30 contact members. The curved tines of the contact members straddle the webs 20' and are resiliently seated on the complementary curved shoulders 21. From this construction it will be noted that contact is always maintained between the contact members and the heating elements over the entire surface of the curved shoulders 21 regardless of the expansion or contraction of the heating elements due to 35 changes in temperature.

40 As shown in Figure 1 the heating elements 18 and 19 pass through apertures formed in the casing 1 and in the muffle 5, and it is to be particularly noted that the muffle 5 is only deep enough to accommodate the heating elements, 45 and therefore has what may be termed a minimum air or gas capacity. This feature is of considerable importance as will be explained later.

45 The top of the casing 1 is covered by means of a disc 22 supported on the shoulder 23 formed on the inner surface of the casing 1. The muffle stem 6 is sealed to the disc 22 by means of a boss 24 depending from the plate 22.

50 The entire cylindrical casing 1 is enclosed by means of a bell 25, the lower peripheral edge of which is supported on a gasket 26, carried in a groove formed in the outwardly extending flange 3 of the casing 1. Screws 27 secure the bell 25 to the casing 1 and hold its peripheral edge 55 sealed against the gasket 26. Gasket washers 28 disposed beneath the heads of the screws 27 prevent the leakage of air or gas outwardly through the bell. The disc 22 and the bell 25 are provided with central apertures 29 and 31 adapted to register with the muffle stem 6, and 60 consequently an unobstructed view into the center of the muffle is permitted. A short stem 32 is provided on the bell 25 and is internally threaded to accommodate a threaded plug 33. Engaged by the plug 33 between two gaskets 34 and 35 is a second transparent quartz or glass 65 window 36 which may be either colored or clear.

70 As shown in Figure 2 the muffle 5 is of a substantially rectangular shape. The stem 6 however is of circular cross-section at its upper end.

but merges with the muffle in an ellipse. This construction therefore gives an extended unobstructed view into the muffle between the heating elements and permits a greater area to be viewed within the muffle than would be permitted by a cylindrical stem. 5

The casing 1 is provided with passageways 37 and 38 which establish communication between the interior of the muffle 5 and a gas receiver which will be explained later in connection with Figure 4. The passageways 37 and 38 are formed in part (as shown in Figure 1) by registering apertures 39, 41, 42, and 43 formed in the plate 7 and in the refractory disc 10.

To the lower end of the carriage or apron 4 is secured a plate 45, by any suitable means, such as screws 46 and threaded to this plate is a screw 47 the lower end of which is provided with a crank 48, while to its upper end is swiveled a plate 49. A cup 51 provided with a flange 52 and formed with counterbores 53 and 53' is secured to the plate 49 by means of screws 54. The flange 52 is formed with diametrically opposed notches 55 adapted to straddle ribs 56 and 57 formed on the interior surface of the apron 4. It will therefore be seen that since by this construction the rotational movement of the cup 51 is prevented, the cup of necessity must move in a vertical direction upon rotation of the crank 48. The upper face of the flange 52 is recessed to accommodate a gasket 58, and alternate rings 59 and 61 are formed on the floor of this recess and on the lower face of the inwardly extending flange 2 for the purpose of biting into the gasket 58 to thereby form a 35 tighter seal between the cup 51 and the flange 2 when the cup is in its uppermost position. If desired the gasket 58 may be held in place by small pins 62 secured to the flange 52, and having their heads bent over into the gasket. 40

Secured within the cup 51 is a sleeve 63 provided with diametrically opposed bayonet slots 64. Disposed within the cup 51 is an investment ring 65 which is adapted to be locked within the cup by the engagement of the bayonet pins 66 within the bayonet slots 64. The lower end of the investment ring 65 is sealed against an annular gasket 67 placed on the floor of the cup 51 and a screen 68 accommodated in the counterbore 53 prevents foreign matter such as particles of investment from plugging the gas outlet 69 provided in the counterbore 53'. The gas outlet 69 communicates through a valve 71 as shown in Figure 4, either with the atmosphere or with a source of vacuum. 55

The contact members 14 and 15 may be connected to a source of electric current by leads (not shown) which may be passed through a suitable air tight connection formed in the casing 1, preferably through the outwardly extending flange 3. The space defined by the inner walls of the casing 1, the muffle 5, and the cover plate 22 is filled with an insulating material such as diatomaceous earth or Diatex. This is not only for the purpose of insulating the muffle, but also for the purpose of keeping the volumetric air capacity of the furnace as low as possible. 60

As shown in Figure 3 the investment ring 65 is provided with two sets of bayonet pins, one set 66, and another set 72 at its opposite end. As has already been explained one set is used for locking the ring within the cup 51. The other set serves as a means by which a pair of tongs having apertured ends may be used to lock 75

the investment ring in place or to disengage it. This feature is of importance, for it has been found that considerable force is sometimes required to disengage the investment ring after it has been subjected to the heat within the muffle, and the application of the ordinary tongs to the periphery of the ring scores the ring within a short time. By making both ends of the ring identical and providing each end with a set of bayonet pins, either end can be made to serve as the bottom or the top and no damage is done to the ring in handling it.

The upper end of the ring is shown as capped by a sprue holder and crucible former 73. This member is used only when the mold within the investment ring is being formed and serves three purposes. A central convex boss 74 forms a concave depression or crucible in the investment material for the metal button used in making the casting. A small hole 75 formed in the boss 74 holds the sprue in place and the sloping walls 76 form an annular shoulder of investment material which completely overhangs or covers the upper peripheral edge of the investment ring. The purpose of this overhanging shoulder is to protect the upper edge of the investment ring against the intense heat to which it would otherwise be directly exposed when within the muffle.

As shown in Figures 1 and 4, pipes 81 communicate with the passageways 37 and 38 leading to the interior of the muffle and are connected by means of a valve 82 with a gas receiver 83. The gas receiver in turn communicates through a pressure reducing valve 84 with a high pressure tank 85. The volumetric air or gas capacity of the muffle 5 should be negligible in comparison with the volumetric capacity of the gas receiver 83.

To fully appreciate this relationship some consideration should be given to the operation of the furnace. After the mold for the casting has been prepared in the investment ring, a button of metal placed in the crucible formed in the upper part of the ring, the investment ring locked in the cup 51 and the cup 51 locked in its uppermost position so as to form a closed chamber with the muffle 5, the heating elements 18 are connected with the source of current. By looking through the windows 11 and 36 which are in axial alignment with the investment ring it can easily be determined when the metal has been heated to a molten state. Previously, the valves 71 and 82 have been closed and the pressure reducing valve 84 adjusted to maintain an operating pressure of say 30 pounds within the gas receiver 83. The pressure within the tank 85 may be of course run as high as 1500 pounds. When the metal within the muffle has been completely melted, valve 82 is opened thereby subjecting the interior of the muffle and the molten metal to substantially the pressure of the gas receiver 83. The molten metal is forced down through the sprue hole into the mold completely filling it and displacing the air which was previously contained therein. This displaced air is driven downwardly through the porous investment material into the bores 53 and 53' of the cup 51. The volumetric capacity of the bores 53 and 53' is of course somewhat greater than the capacity of the mold and sprue hole. The temperature within the muffle is maintained throughout the period that the casting is being made and consequently the metal within the mold tends to solidify from the bottom upwardly instead of in the reverse direction as would be the

case if the heat were discontinued. By having the volumetric capacity of the muffle negligible as compared with the capacity of the gas receiver 83 the molten metal is subjected to a substantially constant pressure. For let V_1 represent the volume of the receiver 83, P_1 its initial pressure, V_2 the combined volume of the muffle and the receiver and P_2 the final equalized pressure within the muffle and the receiver after the valve 82 has been opened. By applying the well known law

$$P_2 = \frac{V_1 \times P_1}{V_2}$$

and bearing in mind that in the present instance V_2 is substantially equal to V_1 , it will be seen that P_2 is substantially equal to P_1 . It is therefore desirable to have a relatively large volume of gas available at substantially the operating pressure and an intermediate receiver answers this requirement most conveniently. In the absence of the gas receiver 83 the gas pressure within the pipes leading from the pressure reducing valve 84 would be materially reduced when the valve 82 is opened for the small quantity of gas contained in this pipe would be expanded into the muffle. By maintaining the capacity of the muffle and the counterbores in the cup 51 as small as possible and using a relatively large gas receiver there is substantially no drop in pressure and consequently a denser and better defined casting can be made.

The design of the investment ring permits of its being manipulated without injury and the shoulder of investment material formed over its free edge protects it from the intense heat to which it would otherwise be subjected. The use of a colored window in the muffle stem reduces the intensity of the light emitted by the molten metal to such an extent that it can be comfortably watched to determine its condition. The complementary curved contacting surfaces of the heating elements and the contact members insures a good electrical connection between these members regardless of any changes in the length of the heating elements due to temperature variations. Furthermore because of its particular design the furnace above described can be easily constructed, operated, inspected and repaired. To disassemble the muffle and replace the heating elements it is only necessary to remove the bell 25 by unscrewing the screws 27. The cup 51 and its operating screw are readily removed by simply unscrewing the screws 46 and the cup itself can be removed by means of the screws 54. The casing 1 and the depending carriage or apron 4 have been made as two distinct elements largely to diminish the transfer of heat from the former to the latter.

For the purpose of making large castings I have shown in Figure 5 a large investment ring which although of a somewhat different construction than the ring above described can be operated in exactly the same manner. As shown the ring has a cylindrical base 91 and tapered open neck 92 which merges with a shoulder 93. The diameter of the base 91 is such that the base can be supported on the gasket 58 of the cup 51 and the tapered neck 92 is small enough to be accommodated within the opening formed at the center of the inwardly extending flange 2. An annular gasket 94 is adapted to be disposed between the shoulder 93 and the lower face of the flange 2 and effects a seal between these two members. This sealing action is aided by the

beads or rings 61 formed on the flange 2 and beads or rings 95 formed of the shoulder 93. When this investment ring is sealed in this way between the cup 51 and the flange 2 the casting operation can be carried out under pressure in exactly the same manner as when a small ring is used and with the same advantages.

5 The screen 68 may be replaced by an inverted cup (not shown) provided with a perforated bottom and disposed within the cup 51 with its bottom (inverted) slightly below the level of the top of the cup 51. In effect this merely raises the level of the screen 68 and decreases the volumetric capacity of the cup 51 when the large 10 investment ring is being used.

15 I claim:

1. A furnace comprising a casing provided with a depending apron; a shallow inverted funnel shaped muffle supported within said casing; a heating element disposed within said muffle at right angles to the axis thereof and a cup slidably associated with said apron and arranged in its uppermost position to close the lower open side of the muffle.

20 2. A furnace comprising a casing provided with a depending generally semi-cylindrical apron; a shallow inverted funnel shaped muffle supported within said casing; a heating element disposed within said muffle at right angles to the axis thereof and a cup slidably disposed within said apron and arranged in its uppermost position to close the lower open side of said muffle.

25 3. A furnace comprising a casing provided with a depending apron; a shallow inverted funnel shaped muffle supported within said casing; a counterbored cup slidably associated with said apron and arranged in its uppermost position to close the lower open side of said muffle; a gas line communicating with the interior of the 30 muffle and a gas outlet provided in the counterbore of the cup.

4. A furnace comprising a casing provided with a depending apron and an inwardly extending flange; a muffle supported on the upper face of said flange and a cup slidably associated with said apron and adapted in its uppermost position to engage the lower face of said flange and thereby form a closed chamber with said muffle.

5 5. A furnace comprising a casing provided with a depending apron and internal and external flanges; a muffle supported on the upper face of said internal flange; a cup slidably associated with said apron and adapted in its uppermost position to engage the lower face of said internal flange; and a bell inclosing said cylindrical casing and supported on its external flange.

10 6. A furnace comprising a casing having inwardly and outwardly extending flanges and a depending carriage; a shallow inverted funnel shaped muffle supported on the upper face of said inwardly extending flange; a counterbored 20 work retaining cup slidably associated with said depending carriage and arranged in its uppermost position to close the lower open face of said muffle, a cover disposed over the upper end of the casing; diametrically opposed recesses formed on 25 the outer surface of the casing and electric contact members supported therein; electric heating elements secured to said contact members and extending through the casing into the muffle; a bell enclosing said casing and supported on said 30 outwardly extending flange; a gas inlet associated with the muffle and a gas outlet associated with said work retaining cup.

7. A furnace comprising a casing provided with a depending apron; a muffle having an open lower 35 face supported within said casing; a screw associated with said apron; and a cup swiveled to the upper end of said screw and adapted in the extended position of the screw to close the open face of the muffle.

40 ELMER H. BERRYMAN.
